M. L. TURNER

SEALING RING FOR JARS

Filed March 30, 1923

Fig. 2.

Inventor:
Martha L. Turner:
by Clyde L. Rogers
her Atty.

UNITED STATES PATENT OFFICE.

MARTHA L. TURNER, OF WEST ROXBURY, MASSACHUSETTS.

SEALING RING FOR JARS.

Application filed March 30, 1923. Serial No. 628,925.

To all whom it may concern:

Be it known that I, MARTHA L. TURNER, a citizen of the United States, and resident of West Roxbury, county of Suffolk, Commonwealth of Massachusetts, have invented an Improvement in Sealing Rings for Jars, of which the following description, in connection with the accompanying drawings, is a specification, like characters on the drawings representing like parts in each of the several views.

This invention relates to rubber or like resilient sealing rings as commonly employed on glass jars for sealing and preserving fruits, vegetables and like food stuffs. A principal object of the invention is to provide such a sealing ring with means whereby the vacuum within the jar may be quickly and easily relieved so that the jar cover may be removed without requiring to be pried off or otherwise forcibly removed. To this end the invention consists in the provision of the rubber sealing ring with a tab or projection at one point thereon and of relatively narrow extent at the locality of the ring periphery whereby on pulling this tab outward, a relatively restricted area of the ring is stretched and thus reduced in thickness sufficiently to permit the ingress of air to relieve the vacuum in the jar. The foregoing and other objects and advantages of the invention will more fully appear from the following detailed description taken in connection with the accompanying drawings, and the distinctive features of novelty will be pointed out in the appended claims.

Referring to the drawings:

Fig. 1 is an elevation showing the sealing ring embodying my invention in one form thereof;

Fig. 2 is an edge view thereof;

Fig. 3 is a plan view of a jar equipped with the invention and illustrating the operation of breaking the seal; and

Fig. 4 is an elevation showing a slightly modified form.

10 indicates a sealing ring which may be generally of usual type adapted to be applied to the top of a jar 11, with the cover 12 resting thereon and suitably secured in place. In accordance with my invention the sealing ring is provided with a tab or projection 13 at one point on the periphery thereof. This tab has a relatively narrow

neck portion 13^a extending from the periphery of the ring and bearing a relatively enlarged head 13^b which constitutes a finger piece or gripping portion. This head may if desired be provided also with a hole 13^c to receive a hook or bar for pulling outward on the tab. In use when it is desired to relieve the vacuum in the jar to permit removal of the cover, the tab 13 is pulled outward either by taking hold of the finger piece head 13^b or by inserting a suitable tool in the hole 13^c. This results in stretching the ring at the locality of the neck portion 13^a, thus reducing the thickness of the ring at this point and permitting the ingress of air is indicated at X. For this result to be accomplished satisfactorily and easily, it is essential that the neck portion 13^a of the tab be relatively narrow, so that the stretching action upon the ring is localized and confined to a relatively small extent thereof; it will be understood that if this were not the case and the tab or projection were joined with the ring in a relatively wide base portion, the stretching action instead of being localized as described would be spread and dissipated over a considerable angular extent of the ring, making it much more difficult, if not impossible to stretch the ring so as to reduce its thickness appreciably or enough to permit the necessary ingress of air. In Figure 4 I show a slightly modified form where the head 130^b constituting the finger piece instead of being located symmetrically on the narrow neck 13^a, extends wholly at one side thereof. The action in this case is precisely the same as already described, the only difference being a matter of preference or convenience in taking hold of the tab to obtain the necessary pull thereon. It is to be particularly understood that my invention does not contemplate the provision of the described tab for use in prying or pulling off the cover forcibly, but instead is limited to the described construction and provision whereby a strictly localized stretch of the ring at a restricted locality thereon is obtained, and whereby the ring at this point only is reduced in thickness definitely and substantially, and enough so as to insure ingress of air adequate to relieve the vacuum within the jar. I am aware that the invention may be embodied in other specific forms without departing from the spirit or essential at-

tributes thereof, and I therefore desire the present embodiment to be considered in all respects as illustrative and not restrictive, reference being had to the appended claims rather than to the foregoing description to indicate the scope of the invention.

Having described my invention, what I claim as new and desire to secure by Letters Patent is:

- 10 1. A resilient sealing ring for jars having a tab projecting from the periphery thereof in a relatively narrow neck portion bearing a relatively enlarged head constituting a finger grip, whereby a tension exerted upon said narrow neck portion results in stretching and reducing the thickness of a

relatively small, closely localized area of the ring to permit venting at such area.

2. A rubber or like sealing ring for jars having a tab projecting therefrom in a relatively narrow neck portion where it joins the ring, and with a relatively enlarged head having an aperture therein and constituting means for pulling the tab straight outward, whereby a tension exerted upon said narrow neck portion results in stretching and reducing the thickness of a relatively small, closely localized area of the ring to permit venting at such area.

In testimony whereof, I have signed my name to this specification.

MARTHA L. TURNER.
